UNITED STATES PATENT OFFICE.

ARTEMAS E. F. HOLDEN, OF CENTRALIA, WEST VIRGINIA.

CHURN-DASHER.

1,326,516.

Specification of Letters Patent.

Patented May 15, 1917.

Application filed March 10, 1917. Serial No. 153,392.

To all whom it may concern:

Be it known that I, ARTEMAS E. F. HOLDEN, a citizen of the United States, residing at Centralia, in the county of Braxton and 5 State of West Virginia, have invented new and useful Improvements in Churn-Dashers, of which the following is a specification.

This invention relates to churn dashers and it consists in the novel features herein- 10 after described and claimed.

An object of the invention is to provide a dasher consisting of a single piece of material in the form of a disk adapted to be applied to the dasher staff of a churn and 15 which operates in the liquid as the said dasher staff is reciprocated vertically to thoroughly and effectually agitate the same whereby the globules of oil are ruptured and the particles of fat are quickly liberated.

With this object in view the dasher is 20 made from a sheet of metal preferably in the form of a disk, the said disk having its central portion and peripheral portion lying in the same plane, the said portions being connected together by radially disposed intermediate portions, there being provided at the 25 edges of the said radially disposed intermediate portions upwardly and downwardly extending flanges pitched at acute angles 30 with relation to the plane in which the central and peripheral portions lie. The said central portion is provided with arcuate incisions and the material at the inner edges of the incisions is formed in semi-conical configuration thereby forming hoods with openings at their outer or larger ends. Each 35 alternate hood is disposed above the plane in which the central portion of the disk lies and the other hoods are disposed below the said 40 plane.

The dasher may be loosely mounted upon the dasher staff or fixed thereto as desired and when the said dasher is loosely mounted upon the dasher staff and as the said staff 45 is reciprocated vertically the hoods at the central portion of the dasher will have a tendency to cast or force the liquid radially with relation to the axis of the staff and the said flanges will operate in the liquid whereby the dasher is turned upon the dasher staff and the features of the dasher will effectually churn the liquid.

When the dasher is fixed with relation to the dasher staff and as the said staff is reciprocated vertically the said hoods will 50 have a tendency to force the liquid radially

with relation to the axis of the dasher staff and the flanges will operate in the liquid and have a tendency to move the same back and forth in a circular path thus effectually agitating the liquid and quickly accomplishing the churning operation.

In the accompanying drawing:—

Figure 1 is a plan view of the dasher;

Fig. 2 is a side view of the dasher staff 65 showing the dasher applied.

The other figures are detail views of the features of the invention.

The churn dasher comprises a disk 1 which is preferably circular in plan and 70 which is formed from a single sheet of metal. The said disk 1 comprises a central portion 2 and a peripheral portion 3, the said portions lying in the same plane and being connected together by radially disposed portions 4 which also lie in the same plane. The radially disposed portions 4 are provided at one edge with downwardly disposed flanges or blades 5 and at their opposite edges with upwardly disposed flanges 80 or blades 6. These flanges or blades are disposed at acute angles with relation to the plane in which the portions 2, 3 and 4 lie. The intermediate portion 1 is provided with a series of spaced arcuate incisions 7 85 and the material of the said portions 1 at the inner edges of the said incisions is formed in the shape of semi-conical hoods 3, the larger ends of which are outwardly disposed thereby providing openings at 90 their outer ends.

Each alternate hood 8 is disposed above the plane in which the central portion 2 lies and the other hoods 8 are disposed below the said plane. In practice, the disk 1 is 95 mounted upon a dasher staff 9 and the said disk may be loosely mounted thereon or fixed thereto. The dasher and dasher staff are intended to be used in a churn body of any usual configuration and during the 100 churning operation the dasher staff is reciprocated vertically.

As hereinbefore stated in the event that the disk 1 is loosely mounted upon the staff and during the vertical reciprocation of the 105 same the hoods 8 will force the liquid radially and outwardly with relation to the axis of the staff 9. Upon the downward stroke of the said staff those hoods 8 which are disposed above the plane of the central portion 110 2 will have a tendency to force the liquid outwardly and radially as stated and upon

the upward stroke of the dasher staff those hoods 8 which are located below the said plane will have the same effect upon the liquid. At the same time the flanges or blades 5 and 6 will operate in the liquid and inasmuch as these flanges or blades are disposed at acute angles with relation to the plane in which the portions 2, 3 and 4 lie, the weight of the liquid in the churn body 10 will have a tendency to cause the disk 1 to swing back and forth upon the dasher staff and thus the currents of liquid which are poured outwardly and radially by the hoods 9 are operated upon by the flanges or blades 15 5 and the adjacent edges of the portions of the disk and hence the liquid is thoroughly agitated whereby the churning operation is facilitated.

In the event that the disk 1 is fixed to 20 the dasher staff the hoods 8 and 9 will force the liquid outwardly and radially as hereinbefore described upon the vertical reciprocation of the dasher and dasher shaft. Inasmuch as the dasher staff is held in the 25 hand of the operator and cannot turn or rotate to any appreciable degree during its reciprocatory movement the blades or flanges 5 will operate in the liquid to cause the same

to move back and forth in circular paths thus agitating the same and accomplishing 30 the churning operation.

From the foregoing description taken in conjunction with the accompanying drawing, it will be seen that a churn dasher of simple and durable structure is provided 35 and that the same may be easily and readily used to effectually and efficiently accomplish the churning operation.

Having described the invention what is claimed is:—

A churn dasher in the form of a disk having central, peripheral and radially disposed portions lying in the same plane, there being provided at the edges of the said radially disposed portions blades which are 45 disposed at acute angles with the said plane, some of the blades being extended above the plane and the others below the said plane and cone shaped hoods provided upon the central portion and disposed some above the 50 plane thereof and the others below the plane thereof, the larger ends of the said hoods being outwardly disposed and open.

In testimony whereof I affix my signature.

ARTEMAS E. F. HOLDEN.
